Primary Examiner — Cynthia R Underwood(74) *Attorney, Agent, or Firm* — Grant's Law firm; Allan Grant(57) **CLAIM**

I claim the ornamental design for a adapter, as shown and as described.

DESCRIPTION

FIG. 1 is a perspective top view of the adapter;
 FIG. 2 is a perspective bottom view of the adapter;
 FIG. 3 is the front view of the adapter;
 FIG. 4 is a back view of the adapter;
 FIG. 5 is a side view of the adapter;
 FIG. 6 is the other side view of the adapter;
 FIG. 7 is a top view of the adapter;
 FIG. 8 is bottom view of the adapter; and,
 FIG. 9 is a cross-section taken in the direction of markers
 "9-9" on FIG. 6.

1 Claim, 2 Drawing Sheets(56)
